Folsom No 44000 221X

Folsom Park

The following notes & drawings show Folsom Park and working plan of the same including a description of the walls of the said Park showing the removal of the improvement in the Stocking Barn

This improvement in the Stocking Barn consists of a framed timbered structure to be according to the following description. A block formed by a plank of hard wood 6 feet long and 6 inches wide having 4 holes 16 inches apart in height, a inner frame 23 inches wide and 10 inches high, situated on the top of the block. The front standards of the frame 12 inches wide plates 16 inches wide held together by 3 horizontal iron bars extending 22 inches long (one at the bottom and one in the middle) driven through them and fastened by a nail and screw at each end at the top of the standards, secured on the inside a horizontal iron bar 16 inches long & one 3 inches from the bottom 7 inches long. The back standards and iron plate 17 1/2 in wide secured in the same parallel to the front standards 4 1/2 inches from them having on the edge towards the front a small projection and on the back edge 3 inches from the top a notch 1 1/2 inches wide cut in as far as the center. a round iron pillar 21 inches long passing through the end of the top bar and fastened by a nail and screw at each end. at the top of the front standards secured on each edge a small iron plate 6 inches wide projecting out 6 inches in front on the top bar, an iron on top plate about 2 inches wide and 10 inches long secured on between the standards having a square top and a round hole 2 inches below the top of the bar, an iron nail 1 1/2 inches diameter the yoke iron working in a plate secured on the back standard over the notch of projecting out at each side of the frame about 5 inches and squared. The end of the nail on the right side of the frame rounded off an inch in length. On the right side of the frame a cast iron standard 12 inches high is secured on the back, having on a narrow side 3 inches long with an hole in the end through which the end of the large nail passes. A standard 18 inches high secured on the back parallel to the office. On each the yoke iron working

in the standards being applied to the ends near the front and a similar angle
near the two standards on the top of the main standard to prevent the
sail from being forced broadways on the large side a regulation 8 inches from
the end of the stern and a pinion on an angle between the regulation on the
large side and 18 inches on the side, and which on the outer end of the small
sail, the angle being formed by the 18 inch pinion on the end and the pinion
on the side of the standard and the regulation on the large side. The large side
makes one turn to the fore of the small sail, & keeps the frame having the ends
fixed in the front standard 2 inches from the top. 2 polished steel bars 8 ft.
and $\frac{1}{2}$ inch $\frac{3}{8}$ of an inch apart one in front of the other. The front bar half
the width of the boat: it stands between the bars formed by the plates of polished
steel cast in lead about 11 pounds each which rest upon the back
bar and are held together by iron or brass plates 3 inches long connected the
top and back of the bars at each end, the steel plates wide in the space between
the bars. see fig 1. on the top of the frame the lead rests on the steel plates &
covers the under side, back and top of the bar, leaving a perpendicular open
ing between each plate for the needles to move in. Through the top of the frame
16 of iron made from the upper edge an aperture $\frac{1}{2}$ of an inch long from the top
of the bar end $\frac{3}{8}$ of an inch wide: at each end of the bar pieces on the
bar a piece of brass or iron of the same form to prevent the stone heads from
hitting. A steel bar called the back
bar being a copy the frame in the spaces in the steel plates projecting
out about $\frac{3}{8}$ of an inch at each side and turned round at the ends on
the upper side of the bar at each end a piece of iron or brass 3 inches long
and on the under side a perpendicular quid formed by a piece of iron bent right
angular on side turned to the bar by 2 screws passing these into the pieces of
iron on the top. The other side of the quid about $\frac{1}{4}$ of an inch from the standard
on each end of the bar and makes a fish bone roller working against the in
side of the standard. The end of the quid rest again a few degrees with the
standard, and on each end of the bar in front of the place a pinion one 18
inches from the top of the bar, the other end against the end of the quid.

the same portion of the plate of the front bar and on the same frame of the middle bar, except on the latter bar the steel plate on the innermost top of the bar about $\frac{1}{4}$ of an inch wide and the end of the top part of the middle bar are each wide. The ends of the plate occupy the outer side of the bar and end towards the needle in a hole at the top of the steel plate. The plates and plates in the ends of the bar hold the bars together. The bars being set in the frame one, front, one over the other, the ends forced in the plates on the front standards. The bars have $1\frac{1}{2}$ inch wide and 1 inch thick. The upper bar is $\frac{1}{2}$ an inch wide and $\frac{3}{8}$ of an inch thick, about 3 inches above and over the inner edge of the outer bar. It rests on the bar formed by three plates of polished steel cast in bars of the same thickness as the middle and back bar frame bars. The plates in form a right angle one side $\frac{1}{2}$ an inch wide, the other one inch wide, on the end of the innermost side of the angle a head cast on having a hole there to fit the upper bar, along the outer edge of the wide side a head cast on about $\frac{1}{2}$ of an inch wide resting on the inner edge bar. On the end of the widest side of the outer plate a round hole one quarter of an inch diameter. The three pieces joined together by bolts in the plates are joined on each side of each end of the small bar and on the top of the inner edge bar. A round steel cast 3 inches long forced thru the bars, i.e. the frame and through the side of the frame for the workers to work upon a middle similar similar to a needle in a common stocking beam (about 2 inches long having a hole in the stem as high as the point of the eye cast in a head or soldered in a steel plate $1\frac{1}{2}$ inches long and $\frac{1}{2}$ an inch wide, each needle plate on the front edge a spring, above the spring a notch $\frac{1}{4}$ of an inch deep & $\frac{1}{4}$ of an inch from the bottom a notch $\frac{1}{16}$ of an inch deep. The middle part between the stem and the spring pressing against the front bar holds it in and admits of its sliding freely up and down. The middle piece of steel about 3 inches long $\frac{5}{16}$ of an inch wide at one end and wide $\frac{1}{4}$ of an inch at the other at the larger end a notch $\frac{1}{16}$ of an inch wide $\frac{1}{16}$ an inch deep. The worker passes through the stem, the small end between the middle piece and laying in the notch at the top of the needle head and the notch at the large end on the side on the outer plate. A hook bar (similar to a hook in a common stocking beam) about $\frac{3}{16}$ of an inch long having

20

up the working part of the standard, so that from end to end it is about $\frac{1}{2}$ of an
inch thick. The sleeve on the tick bar has a hole $\frac{1}{2}$ of an inch from the lower
plate and intended to fit the slotting between the two standards. The tick bar
projects above the edge and over the end of the sleeve to enclose the middle. The
middle is standing above the bar and about $\frac{1}{2}$ of an inch and has a slotting against the
face of the needles, the point entering the slotting the top of the bar a little
nearer than the eye of the needle, and tipped down toward the point. The
tick bar is held in the sleeve by an iron bar laying on top of them and fastened to
the tick bar by a thumb screw at each end. The hole at the end of the
iron bar lengthwise so that the bar can be taken off without drawing out
the sleeve. On the point of the guides of the tick bar, a piece of iron is
welded, proportioned to project the top bar from bearing against the sleeve at
the top of the groove in the steel plate at the top of the standard, a notch about
 $\frac{1}{8}$ of an inch deep. The tick bar when moved up or down, brushed out of the slot
so that the points, may stand clear of the needles. A bar called the gage
is $\frac{1}{16}$ of an inch longer than the distance back of the needles, having $\frac{1}{16}$ of an inch
space between them and the bar. On the top of the sleeve a bar called the stop
bar to hold down the slotting piece when the needles rise up, fastened to the gage
bar by a thumb screw at each end. The holes in the stop bar are lengthwise
so that it can be taken off without drawing out the sleeve. A spring
is wound on each end of the sleeve bar, the end resting against the gage bar
inside of the groove on the large end a solid wheel of brass or iron 3 inches
diameter having 160 needles on the edge about $\frac{1}{4}$ of an inch apart and $\frac{1}{16}$
of the circumference of the wheel in length. A square iron wire called the
weaver or the gaudy wire, is in a loop state secured on the outside of
the standards back of the middle sleeve bar, having one end over 4 inches
long secured over the end and resting against the gage bar; the other
6 inches long secured on the end having at the end a pin resting on the
edge of the wheel on the side. The wire pushes forward the gage bar against
the needles by the wheel rising the pin on the end out of its notch, holds it
against them while they rise up until the tick bar comes down and takes
up the loop. The tick bar then turns them coming under the pin on the side
of the wire. The spring pushes back the gage bar and continues to hold the needles
long

about 2000 lbs. diameter, having a width of 1000 lbs. and a height of 1000 lbs. The center weighing below the top of the frame, on the front on the left hand on the end of the cylinder & a wheel which inside of the frame on the large scale a wheel of 1000 lbs. or iron 4 inches diameter, having a notch on the edge on each side of the center top of the iron made deep like the notches at the top. . . . The iron base 18 inches long resting on a plane at the end of the top bar and the iron standard rest laying between the notched wheel on the cylinder and the wheel on the large scale, having a dimple to catch on the back of the notched wheel on the cylinder, a movable weight and notches cut in the upper edge like a slot yard and a pin on the side to rest on the wheel on the large scale so that the notch on the wheel coming under the pin the lever falls and turns the cylinder. The notch on the wheel is placed that the lever falls when the lower wheel has passed forward the upper bar against the cylinder. On the base bar a spring curved on the end resting on the scale of the cylinder to prevent it from running back when the lever rises up. A movable iron bar resting at the end on the top bar of the frame, having at each end on the inside and upper side a piece of brass or iron 2 $\frac{1}{2}$ inches long, curved together by 3 or 4 pins passing thro the bar. On the bar as many curves as there are notches on the frame and so placed on that the bar being brought forward to the notches they pass between them and rest on the edge of the frame. The curves are smaller (similar to the working sculling) 1 $\frac{1}{2}$ inches long each in a bend as small as the scull bar, having a hole through it to fit the bar. In each end of the curving bar, a chain passed over the pillar of the frame and fastened to a hook at each end of the cylinder. At each side of the frame upon the outside on the large scale a notched wheel of 1000 lbs. is heavier having 4 pins placed at equal distances on the surface 14 $\frac{1}{4}$ in. apart from the edge two on each side, over the wheel a pin is curved on the back standard. The iron base a balanced 1000 lbs. iron bar resting on the first, having an oblong hole at one end thru which the end of the notched wheel passes, and a heavy leaden ball on the other end to counter weight the notched bar. On the inside of the base a piece of steel 3 $\frac{1}{2}$ inches long curved on between the center and ball, the end laying against the

the front of the frame. The pin on the wheel striking the end and the
the bar and part of the catch bar. On the outside of the frame a piece of iron
3 1/2 inches long curved outward on the outside of the catch bar. This end
lay on against the outer surface of the catch. The pin on the wheel striking
the end bends up. The iron end comes on the catch bar the ends of
the bars so inclined that the spoke is off center as it falls on the perpen-
dicular wheel. The wheel makes a smooth flat part of a turn. The catch bar
is, excepting off center of the wheel, one the points of the catch bar enter the
flange with needles about $\frac{1}{16}$ of an inch above the edge of the flange and project
down between the bars. Under the middle frame bars a piece of iron ends standard
1 1/2 inches high & $\frac{3}{16}$ of an inch wide. It has parallel the needle lifter bar
one inch wide, being the frame on the project and projecting out at each
side about an inch, having a round top in each end. On each end a
pinion roller working against the inside of the standard. At bar called
the catch bar to which the needles hold when struck down by the notches
the bottom of the plate. 18 inches long, iron plate and attached to iron
staple bar in iron staple over each end. The staples above and bent down
and secured on the front side of the lifter bar. The catch bar lays on the
lifter bar so as to bring the edge within a perpendicular line to the points
the inside of the front bar of the needle slide. The edge slopes from the top to
the under side having a notch at each end about $\frac{1}{16}$ an inch deep, a
piece of steel three inches long curved on the front bar of the needle slide
one inch and inclined down to the lifter bar and project into the notches
in the catch bar. On each end of the catch bar a spring passed thru the
staples project the bar against the inclined pieces under the needle lifter
bar at each end a regulating yoke formed with a piece of iron about
3 inches long having a notching ticket one end and fastened to the bar by a
thrust screw passed thru it into the bar one end and passed to rest on the bot-
tom of the yoke on the standard. An iron standard 3 inches high
staple bar the frame lies on each side of the frame. Bent at the bottom so
it is off set from the frame as far as the end of the lifter bar.
A piece of steel long and each side of the frame fastened on the standard
at the top yoke which it turns freely, one end on the frame the

The end of the left side of the frame being beyond the large end of the cylinder, it is a solid bar. At the end of the cylinder, there is a pin in the center. On the large end, over the bars on each side of the frame, there are two stones, extending off about $\frac{1}{2}$ an inch from each side of the center of the axle having friction rollers at the ends. The stones are in line to receive the cylinder, being held in place by the wooden and ironing frames. The center of the stones, since the middle of the bar, is about $\frac{1}{2}$ an inch, so as to leave about $\frac{1}{2}$ an inch, operating upon them, which may have been calculated the stones up about one inch. The catch bar does not rest on the rollers in the middle plates by striking against the ironed stones. The catch bar falls, where the end of the arm comes over the end of the catch bar, leaving most the catch bar owing to over the bar. It has lying across the frame over the center stone the only plates through a space in each side, black and propelling, well set of an inch a regulating gauge at each end of the bar formed with the side plate having a notch ^{ready} to fit the bar, and the long groove, these are fastened to the side of the frame by a flat headed screw, spaced two inches from each other, in more frame or side having friction rollers to work upon the under side of the bar & at the bottom of the frame a roller about $\frac{1}{2}$ an inch diameter works upon the ironed and stone the middle stone has to a roller and frame in that ironed having iron. A bar lying across the frame in the front plates $\frac{1}{2}$ an inch from the top, between the arms, & the end catch bar having on it an iron frame or side called the shuttle frame. On top of the frame a piece of steel surrounds one end touching the front of the middle having a piece of steel in it about $\frac{1}{3}$ $\frac{1}{3}$ inch raised an inch above at the end has the end of each arm hole, nicely polished to the head to work the iron the outside of the front end each side under the ends of the large axle. Each about $\frac{1}{2}$ inches diameter having a groove round the iron, and a pin in the center with 12 leaves, and working on an axle screwed into the back standard iron iron brace bent angularly and down on the standard under the wheel to support the end of the axle, under each wheel a spring which is long, curved in the brace & laying against the iron of the wheel on each side having a groove the catch iron which of an inch wider and about

I made the guard at the end of the gun carriage in the same manner as a gun carriage about $\frac{1}{2}$ of an inch thick. Under each end of the gun carriage and shuttle box a box is putty covered with the sides of the former & a small hole there the frame over the putty, & a cord fastened to the shuttle frame at each side, passed over the putty, and then the spring is fastened to the corner wheel at each side of the frame, & is fastened to the shuttle frame at each side passed over the putty & then the spring is fastened to the outer wheel at each side of the frame. One end of the large outer section wheel to turn the roller and shuttle wheel being $\frac{1}{4}$ of a circle of 8 inches in diameter, so placed that the two are one and being down and working on the pinions of the wheels, those on the other end are up. The outer section wheel turns the outer or shuttle wheel by 3 or 4 teeth hence, the outer or outer wheel so as to draw the shuttle partly across the frame before the roller, the section wheel being to operate on the wheel as soon as the shuttle has come down the cords winding around the wheel on each side around the shuttle from the ~~wheel~~ at the other side of the frame. By being passed thru the springs the cords stop the wheel when it comes by striking against the top of the hole thus causing the wheel to stop always at the same place, and preventing the teeth of the wheel from striking on top of the top of the pinion. The shuttle and roller are drawn across the frame to an inch from the end, four $\frac{1}{2}$ of the section wheels at one end of the car. Then by those at the other end. A cylinder of wood 17 inches long & 8 inches diameter, having an iron rule passed thru the center the quadrants fitting the groove in the plates on the top bars of the frame a box at each side of the frame 18 inches long close against the side of the frame over the sides of the roller and shuttle wheel and winding over a screw at the back of the front stand back 16 inches from the top, a thin steel plate and 8 inches long screwed upon the box, 8 inches from the center working loosely under the screw having a hole in it the end for the quadrants of the cylinder to pass thro. in the end of the box a hole or right by which the cylinders are passed together. To prepare the gun for firing the words 10 feet off the top of the stand, put on the gun carriage, & fire the

Now comes the opportunity of the man and master to make all
these parts & take off the top bar & the top bar & the top bar & the top bar
and pass them on the needles, place the web on which the thread is to go into
the holes & to be wound at the back of the loom & the thread through the holes
in the shuttle, wind the end of it round the first needle and pass along a 3
inch needle with the thread double & pass it through the web then pass the
shuttle to draw the shuttle and follow up the loom & when back to the web pass
the shuttle up the loom & and tighten the tension of the web by the using the top
bar, pass on the top bar and come and come it down, turn the web round
in the common box and work an even over the cylinder, pass on the upper
needle and pass the web back in even over the judgment of the cylinder.
Then take off the iron bar and the work being finished between the cylinder it
is drawn off by them. The remaining work is to take off the top
bar and the part that holds on the cylinder and has a narrow i pulling
two or more needles on one needle take away the shuttle and shuttle from the
nearest needle & pass on the long, the weaving pieces in two or more parts the
parts are laid by hand and the last part of shuttle after weaving are left
in these places. By the regulating of the top bar and one the
shuttle passes how the loom can be set to make the web shade in light.
Leave for weaving with work also for double work may be combined
on the same principle as the loom above specified & described. The loom
may be turned by water machinery or by a steam engine.

Reproduced by the Drawing of John Buzin, Jr. in Stocking Loom
The parts are figured in the order as they are described
in the specification.

Fig. 1. The stocking loom in perspective.

- Fig 2. A section of the machine showing the side plates, the
sharpened points the needle, picket and sinker
and an end view of the different bars in the drawing.
- 3. Needle slant bar, the piece marked C, being one
of the slant pieces cast in a lead.
  - 4. Pickle bar, the piece marked A, one of the
slant pieces and Fig 8 a pickle cast in a lead.
  - 5. Sinker slant bar, Bone of its slant pieces.
  - 6. Needle and needle plate.
  - 7. A沉器 (its operation is the same in principle
as the jick of the common stocking
loom and should have been so called)
  - 8. The tickler cast in a lead.
  - 9. A section of fig 1. A is the cam on the
main shaft to lift the lever and weight B.
B is the ratchet wheel on the cylinder on
which the stockings winds.
  - 10. The carrier. The carrier bar and carriers
can be seen on top of the perspective fig 1.
  - 11. Needle lifter bar and catch bar on top.
  - 12. The roller and frame which works the carriers
(or jicks) it answers to what is called
the carrier in the common stocking frame.
  - 13. Shuttle frame.

(Goose sheet accompanying the Patent
returned for record.)
